UNITED STATES PATENT OFFICE.

EARL E. EICKE, OF EAST AUBURN, CALIFORNIA, ASSIGNOR OF ONE-THIRD TO L. A. DURYEA AND ONE-THIRD TO WILLIAM M. HAINES, BOTH OF EAST AUBURN, CALIFORNIA.

SPRING-FITTER.

1,186,559.

Specification of Letters Patent. Patented June 13, 1916.

Application filed May 11, 1915. Serial No. 27,416.

To all whom it may concern:

Be it known that I, EARL E. EICKE, a citizen of the United States, residing at East Auburn, in the county of Placer, State of California, have invented certain new and useful Improvements in Spring-Fitters; and I do declare the following to be a full, clear, and exact description of the same, reference being had to the accompanying drawings, 10 and to the characters of reference marked thereon, which form a part of this application.

This invention relates to improvements in means for fitting and forming vehicle 15 springs of all kinds, the object of the invention being to produce a means whereby this fitting or forming of the said springs can be done in a rapid and efficient manner and the spring tensioned all in one simple operation and with a minimum expense of time 20 and labor.

A further object of the invention is to produce a simple and inexpensive device and yet one which will be exceedingly effective for the purposes for which it is 25 designed.

These objects I accomplish by means of such structure and relative arrangement of parts as will fully appear by a perusal of 30 the following specification and claims.

In the drawings similar characters of reference indicate corresponding parts in the several views.

Figure 1 is a side elevation of the 35 complete mechanism. Fig. 2 is a front elevation of the same. Fig. 3 is a detached fragmentary view of a holding clamp.

Referring now more particularly to the characters of reference on the drawings, the 40 invention first embodies a suitable supporting post or standard 1 bolted or clamped in any suitable manner, as at 2, to the floor or other desired place. On one side of the member 1 is a holding clamp consisting of a 45 fixed rod 3 secured to the post 1 and having a projecting handle 4 hinged to which is a movable rod 5 having a downwardly projecting lug 7 for a purpose as will presently appear.

50 Projecting upwardly from the upper end of the standard 1 is a holding pin 8. Pivotally mounted on the support 1 is a projecting link 9 carrying a pin 10 in its outer end, hinged to which, is a lever 11 having 55 at its upper end a handle member 12. Turn-

able within the lever 11 is a fixed roller 13. At a space slightly above the position of the roller 13, the said lever 11 is provided with long slits 14 movable in which is a pin 15 supported in a link 16 hinged at its 60 upper end to a hand lever 17 projecting adjacent the handle member 12.

On the pin 15 is a roller 18 normally spaced a slight distance from the roller 13. In practice, when the spring is to be fitted 65 or formed, a former spring or other supporting structure 19 is fitted over the pin 8. The new spring 20 is then heated to a pliable heat and is likewise fitted over the pin 8. The two springs are then admitted between 70 the rollers 13 and 18 and the roller 18 is clamped down against them by means of the operator grasping the handle member 12 and lever 17 and drawing them together. Then by operating the lever 11 backward 75 and forward over the springs 19 and 20, the spring 20 will be shaped and formed to conform to the guide spring 19. The new spring is then made to exactly conform to the curvature of the former spring by pressing 80 downwardly along the length of the same.

During the operation above noted, the members 19 and 20 are held against movement by means of the clamp structure which is brought into use by the operator grasping the handle members 4 and 6 and impinging the lug 7 against the two spring members 19 and 20. I provide the roller 18 with a central groove 18^a so that in the event it is desired to form a ribbed spring, the said 90 groove 18^a will allow of the metal being forced therein as the rollers are moved backward and forward, thus forming the rib aforesaid.

From the foregoing description it will be 95 readily seen that I have produced such a device as substantially fulfills the object of the invention as set forth herein.

While this specification sets forth in detail the present and preferred construction 100 of the device, still in practice such deviations from such detail may be resorted to as do not form a departure from the spirit of the invention, as defined by the appended 105 claims.

Having thus described my invention what I claim as new and useful and desire to secure by Letters Patent is:

1. A device of the character described 110 comprising a supporting member, a flat for-

mer mounted on the member, a lever flexibly connected with the support and having a pair of spaced rollers, one on each side of the former, one of said rollers arranged to bear continuously against the former, the other roller being movable and arranged to flatten material between such last named roller and the former as described.

2. A device of the character described comprising a support, a former carried by the support, a link pivotally mounted on the support, a lever pivotally mounted on the link, and a pair of spaced rollers on the lever, one on each side of the former, one roller being movable with respect to the lever as described.

3. A device of the character described comprising a support, a former mounted on the support, a link pivotally mounted on the support, a lever pivotally mounted on the link, a fixed roller disposed on the lever, a

slidable roller mounted on the lever, a hand lever fulcrumed on the first named lever, and a link connecting the slidable roller to the hand lever as described.

25

4. A device of the character described comprising a support, a former carried by the support, a link pivotally mounted on said support, a lever hinged to said link, a fixed roller mounted in said lever, a roller movable longitudinally in said lever and means for controlling the movement of said second named roller, said roller being arranged on opposite sides of such former, as described.

30

35

In testimony whereof, I affix my signature in presence of two witnesses.

EARL E. EICKE.
